(57) **CLAIM**

The ornamental design for plug for apertures, as shown and described.

DESCRIPTION

This Application is related to, and has a common Assignee with, co-pending Utility Application Ser. No. 09/832,620, filed on the same day herewith for “Closure Device For A Pipe/Wall Aperture”.

FIG. 1 is a perspective view of the plug for apertures showing our new design;

FIG. 2 is a left side elevational view thereof, the right side elevational view being identical thereto;

FIG. 3 is a front elevational view thereof, the back elevational view being identical thereto;

FIG. 4 is a bottom plan view thereof; and,

FIG. 5 is a top plan view thereof.
